Primary Examiner — Zenia I Bennett(74) *Attorney, Agent, or Firm* — Warner Norcross + Judd LLP(57) **CLAIM**

We claim the ornamental design for a makeup applicator, as shown and described.

DESCRIPTION

FIG. 1 is a perspective view of a makeup applicator; FIG. 2 is a left side elevation view thereof; FIG. 3 is a left end view thereof; FIG. 4 is a right end view thereof; FIG. 5 is a right side elevation view thereof; FIG. 6 is a top plan view thereof; and, FIG. 7 is a bottom plan view thereof. The broken lines in the figures depict portions of the makeup applicator that form no part of the claimed design.
